UNITED STATES PATENT OFFICE

WILLIAM DUSTIN THOMAS, OF LYNNFIELD, MASSACHUSETTS, ASSIGNEE TO UNITED SHOE MACHINERY CORPORATION, OF PATERSON, NEW JERSEY, A CORPORATION OF NEW JERSEY

SHOE AND SOLE POSITIONING MECHANISM

Application filed September 29, 1931. Serial No. 565,841.

This invention relates to machines for use in the manufacture of shoes and particularly to improved mechanisms for positioning shoes and soles relatively to each other, as, for example, in the cement attaching of soles to shoes.

In relatively locating a shoe and its sole with the aid of mechanism such as that disclosed in the copending application for Letters Patent of the United States Serial No. 414,516, filed December 16, 1929, in the name of Sidney J. Finn, the edge faces of the rear portion of the sole are engaged by one pair of feelers and the sides of the counter portion of the shoe are engaged by another pair of feelers, the pairs of feelers being so constructed and operated that the pair of shoe-engaging feelers is located symmetrically with the pair of sole-locating feelers. This mechanism is satisfactory under conditions where the prefitting of the heel-seat portion of the sole does not extend very far forwardly of the shoe, so that the sides of the rear portion of the shoe at the points where the shoe-engaging feelers contact with them are spaced equally from the longitudinal median line of the sole. Under some conditions, however, for example, where the prefitting of the sole extends so far forward that the untrimmed edge portions of the sole which must be engaged by the sole-locating feelers lie beneath a rear portion of the shoe the sides of which are unsymmetrical, that is, have right and left characteristics, the shoe-engaging feelers which engage these portions of the shoe will not locate the shoe properly with respect to the sole.

Objects of this invention are to provide, in a mechanism of the kind disclosed in the prior application above mentioned, means by which the shoe-engaging feelers may be so set that when they are in shoe-locating position in engagement with unsymmetrical portions of the shoe they will locate the shoe properly with respect to the sole.

In the illustrated embodiment of the invention, the shoe-engaging feelers are each mounted on a lever which is pivoted between its ends to one of the levers which, in the prior construction, carry the feelers. The

rear ends of the feeler levers are connected together and means is provided for moving their rear ends equally in the same direction.

Preferably, and as illustrated, means is also provided by which that movement can be definitely predetermined in accordance with right or left characteristics of the particular shoe at the points where the feelers engage it. In other respects the feelers are operated as in the prior construction, with the result that, when conditions are such that the feelers engage portions of the shoe that are unsymmetrical with respect to the longitudinal median plane which is equally spaced from the sole-engaging feelers, the shoe-engaging feelers can be set, the one toward that plane and the other an equal distance away from it so that the shoe as a whole will be properly located with respect to the sole.

In the drawings,

Fig. 1 is a plan view of mechanism embodying the present invention;

Fig. 2 is a side elevation of Fig. 1;

Fig. 3 is a plan view showing in greater detail the mechanism in connection with which the present invention is employed;

Fig. 4 is a sectional view on the line IV—IV of Fig. 1;

Fig. 5 is a transverse sectional view on the line V—V of Fig. 1; and

Fig. 6 is a view, partly in section, taken on the line VI—VI of Fig. 3.

The improved mechanism having feelers for relatively locating the rear end of the sole and shoe in which such proper relative location is effected notwithstanding the fact that the shoe-engaging feelers may engage unsymmetrical portions of the shoe, is shown generally in Fig. 1, in which the sole-engaging feelers are indicated by the numerals 10, 12 and the shoe-engaging feelers by the numerals 14, 16. The shoe-engaging feelers are carried by levers 18, 20, which are pivoted between their ends at 22, 24 to a carriage 26 which is movable longitudinally of a sole-supporting pad 28 (Fig. 6) more fully described in the application referred to above. The rear ends of the levers 18, 20 have depending pins 30 which engage inclined slots in a plate 38, the plate being urged forwardly

at the proper time by springs which cause the sole-engaging feelers 10, 12 to find a sole located on the pad 28.

The shoe-engaging feelers, as disclosed in the application above referred to, are carried on levers similar to the levers 18, 20, superimposed upon them, and fulcrumed upon the same pins 22, 24. In the present construction, the forward half of the front 10 arm of each of these levers is removed, leaving levers 40, 42 pivoted at 22, 24 and having at their rear ends upstanding pins 44, 46 that engage inclined slots in a longitudinally movable plate 48. In the present construction, shoe feeler levers 50, 52 are pivoted between their ends at 54, 56 to the forward ends of the levers 40, 42. The rear arms of the levers 50, 52 are offset upwardly (Figs. 2 and 4) so as to overlie a cover plate 58 and 20 are connected together by a link 60 the pivots 62, 64 of which are arranged to overlie the pivots 22, 24 of the levers 18, 20 and 40, 42. As best shown in Figs. 4 and 5, the link 60 has a transverse slot 66 in its upper face 25 which is engaged by the head of a pin 68. Overlying the link 60 is a cover plate 70 fixed by screws 71 to the cover plate 58 and spaced therefrom a sufficient distance to accommodate the rear ends of the levers 50, 52, the link 30 60 and the head of the pin 68. Mounted in a counterbored hole in the plate 70 is a circular flanged stud 72 which turns freely therein but is held from upward movement by its flange 73 (Fig. 5). The pin 68 extends upwardly through a hole in the circular stud 72, which hole is eccentric with respect to the stud. The stud 72 has in its upper portion a dovetailed slot 74 to receive a slide 76 which holds the stud from downward movement 35 40 and has an end portion formed to enter any one of a series of notches 78 formed in a semi-circular flange 80 on the cover plate 70, the flange being concentric with the stud. The slide 76 is provided with a finger piece 45 50 82 and has a slot 84 to receive the pin 68, the slot permitting limited endwise movement of the slide. Between the pin 68 and the finger piece 82 is a tension spring 86 which holds the end of the slide 76 in engagement with one 55 60 of the notches 78. By grasping the finger piece 82 and moving the slide against the tension of the spring 86 to free the slide from the notch, the stud may be turned by the finger piece, whereupon the eccentric pin 68 65 70 will act in the slot 66 of the link 60 to move the link endwise and hence to swing the ends of the levers 50, 52 equally in the same direction. When the end of the slide is in engagement with the central notch 78, as shown in Fig. 1, the pin 68 is in alignment, longitudinally of the feeler levers, with the center of the stud and the centers of the end pivots 62, 64 of the link 60 are respectively over the centers of the pins 22, 24. With this setting, 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 10530 10535 10540 10545 10550

the end feeler 90 is held against further movement to the left and accordingly rocks a lever 92 in a clockwise direction, releasing a lever 94 which is moved in a clockwise direction by a spring 96 causing a tooth 98 carried thereby to engage ratchet teeth 100 formed on a relatively stationary member, thus locking the carriage 26 against further movement toward the left. When this occurs, the slide 10 plate 38 is moved forwardly to cause the sole-engaging feelers 10, 12 to find and hold the sole in the position in which it was placed by the operator. The operator then places a shoe A, the overlasted portion of the bottom 15 of which has been scoured and coated with suitable cement, on the sole B and depresses a hand lever 102, thus releasing an angle lever 104 which is then moved in a clockwise direction by a spring 106, one arm of the lever being connected by a pin 108 to the slotted plate 48 so that the plate is moved to the left, causing the shoe-engaging feelers 14, 16 to close upon the shoe and position the shoe with respect to the sole B. Simultaneously with the 20 release of the lever 104, a lever 110 is released and is moved in a counterclockwise direction by a spring 112 to engage a pin 114 carried by the central feeler member 90 and causes the feeler member to be drawn away from the sole. If the side portions of the shoe 25 engaged by the feeler members 14, 16 are unsymmetrical with respect to the shoe bottom, the stud 72 will be released and turned in the proper direction to cause the shoe-engaging 30 feelers 14, 16 to locate the shoe properly with respect to the sole, the shoe-engaging feelers being located by engagement of the slide 76 with one of the notches 78 in a definite, predetermined position.

40 The operator then starts to apply the preliminary pressure and, if conditions are such as to make it desirable, swings a hand lever 116 in a clockwise direction, the lever acting through a link 118 to retract the sole-engaging feelers 10, 12 so that they will not be caught beneath the shoe when final pressure is applied. The operator then trips the machine to apply the final pressure, the carriage 26 being thereupon withdrawn to its inoperative 45 position toward the right. At the beginning of this return movement, the feelers 10, 12 and 14, 16 are separated by movement of the levers which carry them toward the right relatively to the slotted slide members 38, 40. 50 At the conclusion of this movement of the carriage 26, the lever 104 is returned to its inoperative position by engagement of a roll 120 carried by a lever with a relatively fixed cam surface 122, and the latch on the lever 102 becomes operative not only to hold the lever 104 in that position but also to swing and hold the lever 110 against the spring 112 in its inoperative position. The engagement 55 of the tooth 98 with a relatively stationary cam surface 124 rocks the lever 94 in a coun-

terclockwise direction, thus causing the opposite end of the lever to engage a notch in the lever 92, the lever 92 being urged into latching position by the spring 96. By this movement of the lever 92 the feeler member 90 70 will be thrust toward the left into its normal position.

Having thus described my invention, what I claim as new and desire to secure by Letters Patent of the United States is:

1. A machine for use in the manufacture of shoes having, in combination, means for engaging the rear portion of a sole, said means being mounted for floating movement transversely of the sole, a pair of members arranged for floating movement with said means toward and into engagement with opposite sides of the rear portion of a shoe, and means for setting said members in such predetermined lateral offset relation to the sole-engaging means that a shoe having an unsymmetrical heel portion will be properly located thereby with respect to the sole. 80

2. A machine for use in the manufacture of shoes having, in combination, a pair of feelers to engage the edge face of a sole substantially at opposite ends of the breast line, a second pair of feelers to engage the sides of the shoe over the breast line where the two sides of the shoe are unsymmetrical, means for operating the two pairs of feelers to locate them, after they have found the sole and shoe, in predetermined lateral relation whereby the sole and shoe are relatively located, and means for equally and oppositely offsetting one pair of feelers with respect to the other pair so that a sole and a shoe the portion of which that is engaged by said feeler is unsymmetrical may be properly located with respect to each other. 90

3. A machine for use in the manufacture of shoes having, in combination, a pair of feelers arranged for movement widthwise of a sole into engagement with opposite edge portions thereof and mounted for floating movement transversely of the sole, a second pair of feelers arranged for relative movement toward and into engagement with opposite side portions of a shoe to position the shoe relatively to the sole and also mounted for floating transverse movement, means for controlling said movements of the shoe-engaging feelers in their floating movements to follow the shoe-engaging feelers thereby to position the shoe with respect to the sole, and means for setting the shoe-engaging feelers in a predetermined lateral offset relation with respect to the sole-engaging feelers so that the end portion of a shoe the sides of which are not symmetrical with the longitudinal median line of its insole may be located in proper relation to the outsole engaged by the sole-engaging feelers. 110

4. In a machine for use in the manufacture of shoes, shoe and sole positioning mech-

anism comprising a pair of feelers arranged for movement as a unit lengthwise and for relative movement toward each other into engagement with the edge portions of the sole near an end thereof, a second pair of feelers mounted for lengthwise movement with the first pair and for relative movement thereafter toward each other into engagement with a shoe resting on the sole and which is to be positioned relatively to the sole, and means for simultaneously moving the shoe-engaging feelers laterally equally and oppositely with respect to the sole-engaging feelers to adapt them to position a shoe having pronounced right and left characteristics in proper position relatively to the sole held by the sole-locating feelers.

5. A machine for use in the manufacture of shoes having, in combination, a pad upon which a sole and shoe are positioned while sole-attaching pressure is applied, shoe and sole positioning mechanism comprising a pair of feelers arranged for movement as a unit lengthwise of and for relative movement toward each other into engagement with opposite edge portion of the sole upon the pad, a second pair of feelers mounted for lengthwise movement with the first pair and for relative movement thereafter toward each other into engagement with a shoe which is to be positioned relatively to the sole, and means for controlling the widthwise position of the two sets of feelers constructed and arranged to render unequal at the two sides of the shoe the widthwise separation of the work-engaging faces of the shoe-positioning feelers from the work-engaging faces of the corresponding sole-engaging feelers whereby the shoe-engaging feelers when engaging a portion of the shoe having right and left characteristics can be set to locate the shoe properly with respect to its sole.

6. A machine for use in the manufacture of shoes having, in combination, a pair of levers pivoted between their ends, shoe-engaging members mounted upon one end of the levers, a link connecting the opposite ends of the levers, a rotary stud having an eccentric pin engaging a transverse slot in the link, a slide mounted in said stud for movement at right angles to its axis, and means engaging an end of the slide to hold the stud against rotation.

7. A machine for use in the manufacture of shoes having, in combination, a pair of levers pivoted between their ends, shoe-engaging members mounted upon one end of the levers, a link connecting the opposite ends of the levers, a slotted plate mounted over the link having thereon a circular flange, a stud mounted for rotation in the plate concentrically with said flange, a slotted slide mounted in said stud on the upper face of the flange and having an end formed to engage recesses in the circular flange, a pin passing eccentrically through the stud and engaging a transverse slot in the link, said pin passing through the slot in the slide, and a spring connected between said pin and the slide to hold the end of the slide in engagement with the recesses.

In testimony whereof I have signed my name to this specification.

WILLIAM DUSTIN THOMAS.
